COMBINED SEWING MACHINE CABINET AND SEAT

George A. Huth, Jackson, Miss., assignor to Sears,
Roebuck and Co., Chicago, Ill., a corporation
of New York

Application January 13, 1951, Serial No. 13,789

Term of patent 7 years

(Cl. D33—12)

To all whom it may concern:

Be it known that I, George A. Huth, a citizen of the United States, residing at Jackson, in the county of Hinds and State of Mississippi, have invented a new, original, and ornamental Design for Combined Sewing Machine Cabinet and Seat, of which the following is a specification, reference being had to the accompanying drawing, forming a part thereof.

Fig. 1 is a front perspective view of a combined sewing machine cabinet and seat showing my new design;

Fig. 2 is a similar view showing the top in open position and the seat separated from the cabinet; and

Fig. 3 is a fragmentary front elevation of the combined cabinet and seat, on an enlarged scale.

The back and opposite side of the cabinet and unseen sides of the seat are plain.

The characteristic features of my design reside in those portions shown in full lines in the drawing.

I claim:

The ornamental design for a combined sewing machine cabinet and seat, as shown and described.

GEORGE A. HUTH.
